(57) **CLAIM**

The ornamental design for a water filter, as shown and described.

DESCRIPTION

FIG. 1 shows a front/right/top perspective view of a water filter;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof (comprising an indicator for an enlarged view as shown in FIG. 8);

FIG. 7 is a bottom plan view thereof; and,

FIG. 8 is an enlarged top plan view thereof (as indicated in FIG. 6).

The broken lines immediately adjacent the shaded areas represent the bounds of the claimed design while all other broken lines are directed to environment and are for illustrative purposes only; the broken lines form no part of the claimed design.
